UNITED STATES PATENT OFFICE.

ARTHUR WILZIN, OF PARIS, FRANCE.

SCREW-CLOSURE FOR BOTTLES AND OTHER RECEPTACLES.

973,397.

Specification of Letters Patent. Patented Oct. 18, 1910.

Original application filed February 6, 1907, Serial No. 355,986. Divided and this application filed October 11, 1907. Serial No. 937,006.

To all whom it may concern:

Be it known that I, ARTHUR WILZIN, a citizen of the United States, and a resident of Paris, France, have invented certain new and useful Improvements in Screw-Closures for Bottles and other Receptacles, of which the following is a specification.

My invention relates to screw closures for bottles and other receptacles, and particularly to a novel screw cap so constructed and applied as to avoid the objectionable screwing on of the cap after filling the bottle, the tendency of its jarring loose in transportation and to present other important advantages fully set forth hereinafter.

The invention also relates to novel features of the bottle or other receptacle whereby the same coöperates with the cap.

The present application is a division of another application filed by me in the United States Patent Office on February 6, 1907, Serial No. 355,986, which has matured into United States Patent 937,401 dated October 19, 1909; in said earlier application I have claimed an improved method of screw-capping bottles and other receptacles.

In the accompanying drawings, Figures 1 and 2 are vertical sections illustrating one form of my cap and the manner of applying it to a receptacle. Figs. 3 and 4 are respectively a vertical section and an elevation showing another form of my screw cap. Figs. 5, 6 and 7 are respectively an elevation, a vertical section on line A—A of Fig. 5 and a partial horizontal and greatly enlarged section on line B—B of Fig. 5, illustrating a third form of my invention; Fig. 8 is an elevation of the bottle neck used in connection with the cap shown in Figs. 5, 6 and 7. Fig. 9 shows the same bottle neck with the cap shown ready for unscrewing. Figs. 10, 11 and 12 illustrate still another form of my invention, Fig. 10 being an elevation of the bottle neck with the cap applied, Fig. 11 a vertical section of the two, and Fig. 12 an elevation of the bottle neck alone. Figs. 13, 14 and 15 represent a further construction, Fig. 13 showing bottle and cap in elevation, Fig. 14 in vertical section and Fig. 15 being an elevation of the bottle neck alone. Figs. 16 and 17 are an elevation and a plan view respectively of a form of screw cap provided with longitudinal (vertical) ribs or folds, and Fig. 18 shows this cap applied to a bottle.

The neck of the bottle, jar or other receptacle *a*, that is the part adapted to receive the annular portion or flange of the cap, is provided with a screw thread *b*. Adjacent to the threads of this neck I slide or slip axially a cap *c* the flange of which in the form of my invention shown in Fig. 1 is perfectly plain or smooth so that it need not be turned relatively to the bottle to bring the cap home, with the packing disk *d* (of cork or other suitable material) engaging the mouth of the receptacle. Pressure is exerted longitudinally or axially by any well-known or approved mechanism to hold the cap firmly against the bottle's mouth and insure a tight joint. Then, while the cap is so held, it is forcibly pressed inward by any suitable mechanism, so as to cause the flange of the cap to mold itself perfectly against the screw thread *b*. An example of a mechanism suitable for this purpose has been indicated in Figs. 1 and 2 and consists of jaws or rolls *e* provided with elastic (rubber) facings *f* which become deformed under pressure as shown in Fig. 2 thus making the cap conform closely to the shape of the bottle at all points engaged by said jaws or rolls.

Instead of making the flange of the cap perfectly plain, I may form it with an initial or preparatory thread as indicated at *i* in Fig. 3, but the threaded portion of the cap should be of such a diameter that it can be slipped over the neck of the bottle without turning, and when employing a cap having such a preparatory thread, I prefer to make its flange tapering, as shown. The inward or radial pressure applied to this cap in the same manner as above described will complete the shaping or molding of the screw thread on the cap to fit exactly the threaded portion *b* of the receptacle.

I prefer to lock the cap against rotation relatively to the bottle before or while exerting the inward pressure to mold the flange of the cap to the screw threads of the bottle. This locking may be accomplished in various manners. For instance, as shown in Figs. 3 and 4 and also in Fig. 18, the bottle or other receptacle *a* may be provided with a notch *h* below the screw-threaded portion *b* to receive a tongue *g* projected from the lower edge of the cap. Or, as shown in Figs. 5 to 9 the bottle neck *a* may have a screw thread *k* notched or in-

terrupted at l to receive an inwardly bulged portion g^2 on the tongue g^1 . In this case the tongue obviously need not project downwardly beyond the flange of the cap, but I prefer to do this to enable the tongue to be more readily grasped and bent upward when it is desired to release the cap so that it may be turned to open the receptacle. To facilitate this manipulation of the tongue, I 10 may provide a weakened horizontal line m at the upper attached end of the tongue and also, if desired, weakened vertical lines j at the sides of the tongue, so that the latter may be broken off entirely, as shown in 15 Fig. 9. It will be observed, however, that in any event the upper portion of the cap flange, adjacent to the bottom or disk of the cap, is continuous so as to give it the strength and elasticity required to hold the 20 cap in tight engagement with the receptacle along all points of the circumference. This remark also applies to the construction of the locking means illustrated by Figs. 10 to 15. Here the locking element or surface 25 provided on the bottle a below the screw thread b consists, not of a notch, but as an equivalent, of a projection h^1 adapted to be engaged by a concave portion or recess on the tongues g^3 or g^4 respectively. In these 30 two constructions, instead of the merely weakened lines j of Figs. 5 and 7, I have provided slits or incisions j^1 so that the sides of the tongue are perfectly free, its upper end being attached to the cap flange 35 along the weakened line m .

The preferred form of my cap, illustrated in Figs. 16, 17 and 18, is provided in its entire height with longitudinal (vertical) ribs or folds c^1 which have a twofold purpose; first, they render the cap flange expandable and contractile within certain limits so that it may fit the receptacle properly notwithstanding variations or inaccuracies in the diameter and form of the neck. 40 Second, these ribs or folds, which in the finished closure extend across the screw threads of the cap, and project therefrom outwardly (Fig. 18) afford a better hold 45 for the fingers of the person in unscrewing or otherwise handling the cap. The tongue g^5 which in this form of my invention is located between two of the ribs c^1 and projects entirely below the cap flange to enter 50 a suitable notch may be provided with a weakened line m^1 at its upper edge to facilitate breaking off.

It will be understood that vertical ribs or folds such as c^1 may be applied to other forms of screw caps as well.

One great advantage of the screw cap applied as above described is that it fits the screw thread of the receptacle with absolute accuracy, even when said thread is irregular as it unavoidably is when molded. An ordinary screw cap necessarily has its thread

widened when screwed down over a somewhat irregular thread on the bottle, and therefore does not fit perfectly tight. My cap, however, is not screwed on or turned when it is first applied to the receptacle, 70 and no widening of the thread can occur, but a perfect fit is obtained. A further advantage of my invention is the rapidity of the closing operation, much less time being required to slip the cap into position and then mold it against the threaded neck than to screw a cap home. Still another advantage is the possibility of using machinery for screw-capping receptacles; with ordinary screw-caps this could not be done efficiently, for the reason that it would be impossible to determine whether or not the cap was screwed on far enough and there would be danger of stripping the thread on the cap or breaking the receptacle if the cap were screwed too far. The longitudinal (vertical) ribs are of advantage in enabling the cap to expand or contract and thus fit necks of different diameters and shapes within certain limits; moreover, as above explained, these ribs afford the user a better hold in unscrewing the cap and screwing it on again. The locking tongue prevents the cap from turning relatively to the bottle during the process of molding the cap flange 95 against the threaded neck, as also during transportation, so that the cap cannot be jarred loose. At the same time, the presence of an uninjured tongue indicates to the consumer that the receptacle and contents are 100 still in their original condition, for in turning the tongue away from the neck to release the cap, the tongue is either broken off completely (Fig. 9), or at least so altered in appearance as to show plainly that it has been 105 tampered with. Of course, after the cap has been unscrewed, it can be screwed on by hand like an ordinary screw cap for closing the receptacle temporarily, as in this case the joint need not be so tight as when the 110 bottle is closed for the first time.

I claim as my invention:

1. The combination of a receptacle having a screw thread and a locking surface at a different level, with a cap provided with a 115 threaded flange in engagement with said screw thread, said flange having longitudinal ribs on its entire height extending across its threads, and a tongue projecting from the edge of said flange and in locking engagement with said locking surface to keep the cap from turning relatively to the receptacle, the attached end of the tongue being connected with the flange along a weakened line.

2. The combination of a receptacle having a screw thread and a locking surface at a different level, with a cap provided with a threaded flange in engagement with said screw thread, a tongue projecting from the 130

edge of said flange and in locking engagement with said locking surface to keep the cap from turning relatively to the receptacle, and longitudinal ribs concaved toward 5 the axis of the receptacle and extending across all the threads of the cap.

3. The combination of a receptacle having a screw thread and a locking surface at a different level, with a cap provided with a 10 threaded flange in engagement with said screw thread and a tongue projecting from the edge of said flange and in locking engagement with said locking surface to keep the cap from turning relatively to the receptacle, the attached end of the tongue being 15 connected with the flange along a weakened line.

4. A closure cap provided with a threaded flange which has longitudinal ribs extending 20 across its threads, and also a tongue adapted for locking engagement with the recep-

tacle, the attached end of said tongue being connected with the flange along a weakened line.

5. A bottle cap provided with a flange the 25 upper part of which, at least, is circumferentially continuous, said flange having a screw thread opening out at the bottom thereof, inwardly concaved longitudinal ribs intersecting all the screw threads and 30 extending the whole height of the flange, and a locking element attached to said flange and adapted to be readily detached therefrom.

In testimony whereof I have hereunto set 35 my hand in the presence of two subscribing witnesses, this 8th day of October, 1907.

ARTHUR WILZIN.
